UNITED STATES PATENT OFFICE.

HARRY WILSON AND ARTHUR H. CHASE, OF WASHINGTON, DISTRICT OF COLUMBIA, ASSIGNEES, BY DIRECT AND MESNE ASSIGNMENTS, TO THE UNITED STATES ORDNANCE COMPANY, OF WASHINGTON, DISTRICT OF COLUMBIA, A CORPORATION OF VIRGINIA.

PERCUSSION-FUSE.

No. 806,859.

Specification of Letters Patent.

Patented Dec. 12, 1905.

Application filed March 28, 1905. Serial No. 252,574.

To all whom it may concern:

Be it known that we, HARRY WILSON and ARTHUR H. CHASE, citizens of the United States, residing at Washington, in the District of Columbia, have invented certain new and useful Improvements in Percussion-Fuses, of which the following is a specification.

Our invention relates to that class of fuses for explosive projectiles in which the percussion element is released only by centrifugal force, such as is due to the rotation of the projectile in flight when fired from a rifled gun.

The object of our invention is to simplify and improve the structure and operation of such fuses to insure greater safety in handling the projectiles and certainty in exploding the shell after it strikes the target.

Another object of our invention is to provide improved means for preventing communication from the primer to the magazine of the fuse until immediately preceding the detonation of the primer by the percussion element whereby explosion of the projectile is prevented, even though premature explosion of the primer takes place from causes other than its detonation by the percussion element of the fuse.

With the above and other objects in view the invention consists in the details of construction and in the arrangement and combination of parts to be hereinafter more fully set forth and claimed.

For a better understanding of the invention reference will be had to the accompanying drawings, wherein like characters denote corresponding parts in the several views, and in which—

Figure 1 is a longitudinal section of our improved fuse, showing the various parts in their inactive position; Fig. 2, a similar view showing various parts in position assumed upon initial movement of the percussion-hammer after retardation of the projectile; Fig. 3, a similar view showing various parts in position assumed after complete movement of the percussion-hammer upon impact of the projectile; Fig. 4, a detail plan view of the percussion-hammer shown in Figs. 1, 2, and 3; Fig. 5, an end view of same looking from the rear; Fig. 6, a detail view, partly in section, showing the engagement between the driving-pins of the firing-hammer, the sleeve D, and the stock A; and Fig. 7 is a section on the line x x of Fig. 4 and the line 7 7 of Fig. 6.

Referring to the drawings, A represents a fuse-stock of the usual well-known construction. Secured in the fuse-stock is a primer-supporting plug B. This plug is provided with screw-threads adapted to engage corresponding threads in the stock and is situated a short distance from the open end of the stock. The open end of the stock is closed by a suitable disk Y, and the space between the plug and the disk is filled with powder to form the magazine of the fuse.

The firing-hammer of our fuse is comprised of the segments C C', provided with registering apertures C² C³ to receive the body of a bolt C⁴, which is provided with the enlarged ends C⁵ C⁶. Springs C⁷ C⁸ are interposed between the enlarged ends C⁵ C⁶ of the bolt and the shoulders C⁹ C¹⁰ in the apertures C² and C³, whereby the segments C C' are normally pressed together. The forward ends of the segments C C' are provided with the longitudinally-extending flanges C¹¹ C¹², which form a centrifugally-released locking means adapted to normally engage the primer-plug B and lock the firing-hammer against forward movement. A transverse projection C¹³ on the rear end of the segment C rests in a cut-away portion C¹⁴ in the segment C', and a transverse projection C¹⁵ on the forward end of the segment C covers the forward end of the segment C'. By this construction any longitudinal movement of the segments C C' with relation to each other and consequent strain on the bolt C⁴ is prevented. The projection C¹⁵ carries the firing-point C¹⁶, which in conjunction with the segments C C' forms the firing-hammer or primer-exploding means. The firing-hammer is loosely mounted in the sleeve D, which is arranged loosely in the chamber of the fuse-stock, so as to move freely therein. The firing-hammer is held centrally in the sleeve by the bolt C⁴, which is of a length equal to the inner diameter of the sleeve. To assist the segments C C' to immediately receive the influence of centrifugal force due to the spinning of the shell, we provide the segments C C' with the rearwardly-extending driving-pins C¹⁷ C¹⁸, respectively, which project through the apertures D' D² in the sleeve and into cylindrical recesses A' A² in the rear wall.

of the chamber of the fuse-stock. The apertures $D'D^2$ and the recesses $A'A^2$ are of a size sufficient to permit a limited movement of the driving-pins $C^{17}C^{18}$ therein. It will be obvious that were the segments $C'C'$ mounted without engagement with the fuse-stock they would tend to remain at rest independent of the rotation of the shell and together with the flanges C^{11} and C^{12} would fail to move transversely with the desired promptness. By the construction shown, however, the rotation of the shell will be imparted at once to the segments $C'C'$ and flanges C^{11} and C^{12} , and the co-action arising from the engagement between the cylindrical walls of the recesses $A'A^2$ and the driving-pins C^{17} and C^{18} as a result of the tendency of the segments to remain at rest will aid said segments and the flanges carried thereby in their transverse movement to effect the unlocking of the primer-exploding means. A ball C^{19} is seated in oppositely-disposed registering pockets C^{20} and C^{21} in the segments $C'C'$, respectively, said pockets being situated off the longitudinal axis of the fuse, whereby the ball is adapted to move outwardly under the influence of centrifugal force during the spinning of the shell and lock the segments in their expanded or armed position.

The plug B is provided centrally with an inwardly-extending projection B' , in which is seated the primer B^2 . The annular recess B^3 , formed between the periphery of the projection B' and the cylindrical wall of the fuse-chamber, receives the flanges $C^{11}C^{12}$ upon impact of the firing-hammer after discharge of the projectile from the gun and permits the explosion of the primer by the firing-point C^4 , which is moved centrally of the primer by the transverse movement of the segment $C'C'$. A channel B^4 , leading from the primer to the magazine of the fuse, passes longitudinally through the plug B and is interrupted by a transverse recess B^5 in said plug. A valve B^6 is mounted in the recess B^5 , capable of limited movement therein. The outer end of the valve is provided with the conical surface B^7 , and the inner end is formed with a pocket B^8 to serve as a seat for one end of the spring B^9 . The other end of said spring bears against the closed end of the recess. To hold the valve B^6 in the recess B^5 , we provide a longitudinally-movable piston formed with an enlarged head B^{10} , seated in a recess B^{11} at right angles to the recess B^5 , said head B^{10} terminating in a conical surface B^{12} , normally abutting the conical surface B^7 of the valve. A stem B^{13} extends rearwardly from the head B^{10} a distance slightly less than the length of the projection B' and lies partly in a groove in said projection and partly beyond the periphery of the projection, whereby forward movement of the firing-hammer in its armed position will cause the piston to move forward. Said forward movement of the piston and the resulting coaction between the conical surfaces B^{12}

and B^7 causes the valve B^6 to move inwardly of the recess B^5 and compress the spring B^9 . It will thus be obvious that when the valve B^6 is in its normal position (shown in Fig. 1) premature explosion of the primer could not communicate with the magazine on account of the interposition of the solid part of the valve B^6 in the interrupted portion of the channel B^4 . A channel B^{15} is provided transversely of the valve B^6 and is adapted to align with the channel B^4 when the valve B^6 has moved inwardly, so that the extreme outer end of the valve B^6 registers with the cylindrical surface of the head B^{10} of the piston. (See Fig. 2.) The relative movement between the piston and the valve is so proportioned that the channel B^{15} will align with the channel B^4 immediately preceding the penetration of the primer by the firing-point. The force of the spring B^9 under normal conditions is sufficient to prevent by the engagement of the flange C^{12} with the stem B^{13} of the piston any tendency of the firing-hammer to creep during flight of the projectile. The valve B^6 is held against turning in the recess B^5 in any suitable way, as by means of the pin B^{16} , projecting into a groove B^{17} , as shown in Figs. 1, 2, and 3. For convenience of assembling the piston in operative position we provide an aperture in the plug B in alignment with the recess B^{11} , and after the piston is mounted in operative position close the aperture by means of the threaded nut B^{18} .

To delay the explosion of the magazine of the fuse, a train of slow-burning powder is filled in the channel B^{15} , whereby the passage of the flame from the primer through the channel B^4 to the magazine is retarded.

The operation and advantages of our invention will be at once apparent from the foregoing description; but we desire it understood that various changes in the construction, combination, and arrangement of parts might be made which could be used without departing from the spirit of our invention.

Having thus described our invention, what we claim as new, and desire to secure by Letters Patent, is—

1. In a percussion-fuse a seat for a primer, a channel leading from said seat to the shell charge, a valve closing said channel and means whereby said valve is shifted by impact of the projectile after discharge.

2. In a percussion-fuse, a seat for a primer, a chamber for an igniting charge, a channel leading from said seat to the said chamber, a valve closing said channel and means whereby said valve is shifted by impact of the projectile after discharge.

3. In a percussion-fuse, a seat for a primer, means for exploding the primer upon impact of the projectile, a channel leading from the primer-seat to the shell charge, a valve closing said channel and means whereby said valve is shifted by impact of the projectile after discharge.

4. In a percussion-fuse, the combination with a primer-seat and primer-exploding means, of a channel extending forward from the primer-seat to the shell charge, a valve closing said channel and arranged to be shifted by impact of the projectile after discharge. 5. In a percussion-fuse, a seat for a primer, a firing-hammer, means for holding the firing-hammer inactive, a valve leading from the primer-seat to the shell charge, a valve closing said channel and means whereby said valve is shifted by impact of the projectile after discharge. 6. In a percussion-fuse, a primer-seat, a channel leading from said seat to the shell charge, a valve closing said channel, a second channel in said valve normally out of alignment with the first-named channel and means whereby the valve is shifted by impact of the projectile after discharge and the channel of the valve alined with the channel leading from the primer-seat. 7. In a percussion-fuse, a primer-seat, a channel leading from the primer-seat to the shell charge, a valve closing said channel, a second channel in said valve normally out of alignment with the first-named channel and means actuated by impact of the projectile to aline the valve-channel with the channel leading from the primer-seat. 8. In a percussion-fuse, a primer-seat, means for exploding the primer upon impact of the projectile, a channel leading from the primer-seat to the shell-charge, a valve closing said channel, a second channel in said valve normally out of alinement with the first-named channel and means actuated by impact of the projectile to aline the valve-channel with the channel leading from the primer-seat. 9. In a percussion-fuse, a primer, a primer-seat, primer-exploding means, a channel leading from the primer-seat to the shell charge, a valve closing said channel, a second channel in the valve housing a powder-train of slow explosive normally out of alinement with the first-named channel and means actuated by impact of the projectile to aline the valve-channel with the channel leading from the primer-seat. 10. In a percussion-fuse, a seat for a primer, a channel leading from said seat to the shell charge, a valve closing said channel and means whereby said valve is shifted after discharge independent of the rotation of the projectile. 11. In a percussion-fuse, the combination of a casing, a primer, primer-exploding means, locking means normally holding the primer-exploding means inactive and adapted to be unlocked by the action of centrifugal force and means operating independent of the action of centrifugal force for imparting the initial unlocking movement to the locking means. 12. In a percussion-fuse, the combination of a casing, a primer, primer-exploding means, locking means loosely mounted in the casing normally holding the primer-exploding means inactive and adapted to be unlocked by the action of centrifugal force and means operating independent of the action of centrifugal force for imparting the initial unlocking movement to the locking means. 13. In a percussion-fuse, the combination of a casing, a primer, primer-exploding means, locking means normally holding the primer-exploding means inactive and adapted to be unlocked by the action of centrifugal force and means interposed between the locking means and the casing operating independent of the action of centrifugal force for imparting the initial unlocking movement to the locking means. 14. In a percussion-fuse, the combination of a casing, a primer, primer-exploding means, locking means loosely mounted in the casing normally holding the primer-exploding means inactive and unlocked by the action of centrifugal force and additional means loosely contacting with said casing, but adapted to positively engage the same and thereby immediately impart to the locking means the full rotation of the shell.

In testimony whereof we affix our signatures in presence of two witnesses.
